UNITED STATES PATENT OFFICE.

ERNST W. JOHNSON, OF BROOKLYN, NEW YORK.

AUTOMATIC CARBURETER-AIR-SUPPLY REGULATOR.

1,117,676.

Specification of Letters Patent. Patented Nov. 17, 1914.

Application filed October 29, 1913. Serial No. 797,918.

To all whom it may concern:

Be it known that I, ERNST W. JOHNSON, a citizen of the United States, and residing at Brooklyn, in the county of Kings and State of New York, have invented certain new and useful Improvements in Automatic Carbureter-Air-Supply Regulators, of which the following is a specification, such as will enable those skilled in the art to which it appertains to make and use the same.

This invention relates to the carbureters of automobiles or power driven vehicles, and the object thereof is to provide improved means for regulating the supply of air to said carbureters, and the invention consists in an air supplying device connected with the carbureter or manifold thereof and having a gravity control and also a control adapted to be operated by the fan used for cooling the engine.

The invention is fully disclosed in the following specification of which the accompanying drawings form a part, in which the separate parts of my improvement are designated by suitable reference characters in each of the views, and in which:—

Figure 1 is a view of a part of the manifold of the carbureter of a gas engine and showing my improved air supply regulator connected therewith;—Fig. 2 a section on the line 2—2 of Fig. 1;—Fig. 3 a section on the line 3—3 of Fig. 2;—Fig. 4 a view similar to Fig. 1 but omitting the manifold and showing a modification partly in section, and Fig. 5 a section on the line 5—5 of Fig. 4.

In the accompanying drawings, Figs. 1 to 3 inclusive, I have shown at *a*, a part of the manifold of the carbureter of a gas engine used in connection with a power driven vehicle, and said manifold is provided with an aperture *a*², and secured thereto and inclosing said aperture in an air inlet box *b* having a closed outer end *b*² in which are formed air inlet apertures *b*³ shown in full lines in Fig. 2, and indicated in dotted lines in Figs. 1 and 3. Mounted on the closed outer end *b*² of the box *b* is a gravity operated rotary register valve or valve plate *c* having apertures *c*² similar to those in the end *b*² of the box *b*, and adapted to register therewith, and the rotary plate *c* is mounted on a screw, pin, or bolt *d* secured centrally in the outer end *b*² of the box *b* and on which is mounted a spiral spring *d*² which bears on the plate *c*. The plate *c* is provided with

a depending pendulum *e* consisting of the usual rod *e*² and weight *e*³, and secured to the end *b*² of the box *b* rearwardly of the pendulum is a stop pin *f* adapted to limit the backward movement of said pendulum. Pivoted over the plate *c* on a pin or screw *g* secured in the end *b*² of the box *b* is an arm *h* provided with a fan *h*², and the arm *h* is provided with a cam head *h*³ adapted to bear on a stop pin *i* secured to the end *b*² of the box *b* and forwardly of which the plate *c* is provided with a stop pin *i*², and the head *h*³ of the arm *h* is provided with a nose *h*⁴ which operates in connection with said pin *i*².

The operation of this construction will be readily understood from the foregoing description when taken in connection with the accompanying drawing and the following statement thereof. In the position of the parts shown in Fig. 1, no air will enter through the box *b*, and this is the position assumed by the parts when the vehicle is going down hill, or in the direction of the arrow *X*, or when said vehicle is coasting. When the vehicle is going up hill, as indicated by the arrow *X*², the pendulum *e* and arm *h* will assume the position indicated at *Y* and *Y*², and the air ports or apertures in the plate *c* and the end *b*² of the box *b* will be fully opened. When the vehicle is running on a level surface, or road, the wind from the fan used for cooling the motor will strike the fan *h*², as indicated by the arrow *X*³, and if a high speed is obtained, the fan *h*² and arm *h* will be thrown into the position shown at *Y*², in which position the air ports or passages in the plate *c* will be fully opened, and it will also be understood that this operation is a gradual one and said air ports or passages being gradually opened to the fullest extent, and at the same time the pendulum *e* will be moved into the position shown at *Y*, and said pendulum will operate at the same time to gradually return the parts to the position shown in full lines in Fig. 1.

From the foregoing description it will be seen that with this construction, the supply of air, in the first instance, is automatically controlled by gravity throughout the operation of the pendulum *e* which serves as a weight, and in the second instance, by wind from the fan operated by the revolutions of the fan for cooling said engine, and in Figs. 4 and 5 I have shown a modification in

which the essential features, or main operative parts are the same.

In the construction shown in Figs. 4 and 5, I substitute for the box *b* a circular casing *j* provided on the back side thereof and adjacent to the perimeter thereof with a tubular neck *j*² the end of which is threaded, as shown at *j*³, and adapted to be screwed into the manifold *a*, and that portion of the side 10 of the casing *j* with which the tubular neck *j*² is connected is thickened, as shown at *j*⁴, and provided with a plurality of ports or 15 passages *j*⁵, only two of which are shown and any desired number of which may be employed, and said ports or passages are shown in section in Fig. 5 and indicated in dotted lines in Fig. 4. Passing through the casing *j* and through the thickened portion *j*⁴ thereof and into the tubular neck *j*² is a 20 shaft *k* provided with a register valve plate *k*² which takes the place of the plate *c*, in Figs. 1 to 3 inclusive, and the front end of said shaft is provided with a pointer *k*³ movable over the front face of the casing *j*, and 25 the other or rear end thereof within the neck *j*² is provided with a spring *k*⁴ which normally serves to hold the register valve plate *k*² in a closed position, and said valve plate *k*² is provided with ports or passages *k*⁵ 30 similar to the ports or passages *j*⁵ and two of which are shown. The register valve plate *k*² is provided adjacent to one side edge thereof with a pin *k*⁶ on which is mounted a weight *k*⁷ which takes the place of the pendulum *e*, shown in Figs. 1 to 3 inclusive, and this weight normally aids in holding the register valve plate *k*² in the closed position, as indicated in Fig. 4. Mounted diametrically of the casing *j* and at right angles to 40 the shaft *k* is a shaft *m* one end portion *m*² of which passes through the corresponding side of said casing, and a flexible shaft *m*³ is connected therewith, and a pulley *m*⁴ is connected with said flexible shaft, and in the 45 use of this device, the pulley *m*⁴ bears on the fly wheel of the engine, not shown, so as to rotate the shaft *m*. The shaft *m* passes through a governor ring *o* which is connected therewith by a pin *o*² passed therethrough 50 and through the sides of said ring and through a collar *o*³ mounted on said shaft, and the shaft *m* also passes through a circular disk *o*⁴ slidably mounted on said shaft and between which and the collar *o*³ is placed a spiral spring *o*⁵, and one side portion of the ring *o* is connected with the disk *o*⁴ by cord or other flexible device *o*⁶. The disk *o*⁴ is provided with a deep annular groove *o*⁷ and the register valve plate *k*² 60 with a finger *p* which operates in said groove, and I also provide a fan *r* having a handle *r*² which passes through the slot *r*³ in the face of the casing *j*, and which is pivoted to a support *r*⁴ in said casing, and in the 65 same diametric plane with the shaft *k*, and

the handle *r*² of the fan *r* is provided with a finger piece *r*⁵ which also operates in the groove *o*⁷ of the disk *o*⁴. The face of the casing *j* is also provided with a curved scale plate *s* in connection with which the pointer *h*² 70 operates, and this plate is provided with numerals representing tens and multiples thereof from zero to seventy, and in the operation of the engine, the pointer *h*³ moves over said scale plate and indicates the speed 75 of the motor. The operation of this form of construction will be readily understood from the foregoing description when taken in connection with the accompanying drawings and the following statement: The normal 80 position of the parts is that shown in Fig. 4, and when the apparatus is in operation, the pulley *m*⁴ bears on the fly wheel of the engine, and the shaft *m* is rotated and as the speed increases, the governor ring *o* will assume the position shown in dotted lines, and the disk *o*⁴ will also move into the position shown in dotted lines, and this will open the register valve plate *k*² and increase the supply of air to the engine, and this operation of the governor will be aided by the fan *r* which is operated by the air from the fan by which the motor is cooled, as hereinbefore set out in the description of the operation of the construction shown in Figs. 1 to 95 3 inclusive. Of course, the weight *k*⁷ and spring *o*⁵ always tend to return the parts to the position shown in full lines in Fig. 4, and it will thus be seen that the operation of this form of construction will be the same 100 and will produce results similar to those produced by the operation of the construction shown in Figs. 1 to 3. It must be borne in mind, however, that while I prefer to use the fan *r*, in the construction shown in Figs. 105 4 and 5, this form of air supply regulator for carbureters may be used in connection with motors which do not employ cooling fans in which event the fan *r* of this form of construction would not be necessary. 110

In the construction shown in Figs. 4 and 5, the operative parts are mounted in a closed casing and when this is done the said casing must be provided with openings, 115 ports or passages for admitting air thereto and two of said openings, ports or passages are shown at *t*, and others may be employed and air will also be free to enter through the slot *r*³.

Having fully described my invention what 120 I claim as new and desire to secure by Letters Patent is:—

1. The combination with the carbureter of a power driven vehicle of an air supply device having a rotary valve and a weight 125 adapted to rotate said valve, and means, whereby the operation of the engine will also rotate said valve.

2. The combination with the carbureter of a power driven vehicle of an air supply de- 130

vice having a rotary valve plate provided with a weight which aids in closing it, and means, including a fan operated by the fan employed for cooling the engine, to open 5 said valve plate.

3. The herein described air supply regulating device for the carburetor of a power driven vehicle, said device being provided with a rotary valve having a weight which 10 aids in closing it, and said valve being adapted to be opened by means operated by the engine of the vehicle.

4. The combination with the carburetor of

a power driven vehicle, of an air supply device having a gravity operated rotary valve, 15 and means whereby the operation of the engine will also rotate said valve.

In testimony that I claim the foregoing as my invention I have signed my name in presence of the subscribing witnesses this 20 28th day of October 1913.

ERNST W. JOHNSON.
